TOY

Daniel C. Dozier, Norfolk, Va.

Application November 15, 1946, Serial No. 710,076

15 Claims. (Cl. 46—100)

1

The present invention relates to a child's mechanical toy, and more particularly to a mechanical toy of the kinematic type adapted to be actuated solely by gravity and wherein a simulated animal figure or other object is caused to move back and forth along an inclined track by alternately tipping the latter into oppositely inclined positions.

The principal object of the invention is to provide a kinematic toy of the type described which may be easily set in operation by children and which will continue to operate in an engaging fashion over an extended period of time as compared with the brief interval required to initiate such operation.

Another object of the invention is to provide a toy of the type described involving a relatively few working parts which may be expeditiously and inexpensively produced almost entirely from metal stampings or the like and which is not likely to become out of order under conditions of strenuous usage.

A further object of the invention is to provide a kinematic toy of the type described which operates entirely by the force of gravity after having once been set in starting position and thus requires no external power source for its practical operation so that it may be placed in the hands of very small children with safety.

Other objects and advantages of the invention will become apparent during the course of the following description.

In the drawings I have shown one embodiment of the invention. In this showing:

Fig. 1 is a front elevation of the toy illustrating successive positions of certain of the parts in broken lines;

Fig. 2 is an enlarged fragmentary sectional view on line 2—2 of Fig. 1;

Fig. 3 is an end view of the toy, a portion of the housing being broken away to illustrate the interior construction;

Fig. 4 is a fragmentary detail sectional view to an enlarged scale of a portion of one of the vertical supports taken substantially along the line IV—IV of Fig. 2;

Fig. 5 is a detail perspective view to an enlarged scale of one of the crossheads and a fragment of the transverse rail constituting a part of the present invention; and

Fig. 6 is a detail perspective view illustrating to an enlarged scale the movable carriage and simulated animal figure carried thereby.

Referring to Figs. 1 and 2, the device comprises an elongated base 10 having a pair of upright

supports 12 extending substantially vertically upward adjacent its opposite ends and including a crossbrace 14 extending transversely between said supports. Each of the supports 12 is provided with a generally tubular housing 16, having flanges 18 (Figure 2) adapted to be secured in any convenient manner to the outer faces of the supports 12. The base 10, supports 12, and crossbrace 14 constitute a relatively fixed framework for the toy, preferably being formed of light metal stampings or the like and assembled together in any suitable manner as, for example, by spot welding. Alternatively, suitable threaded or other similar connecting means may be provided to releasably secure these members together so that the toy may be readily dismantled for storage or shipment, if desired.

Referring to Figs. 2 and 3, it will be noted that each of the supports 12 is actually formed of a pair of horizontally spaced stampings 20 having their inner edges suitably bent to form a pair of tracks 22 defining a guideway 24 opening into the interior of the housing 16. A pair of vertical racks 26 each having a plurality of teeth 28 formed thereon is suitably attached in any convenient manner to the members 20 at each side of the guideways 24 within the housings 16.

As will be particularly noted in Fig. 1, the teeth 28 of the pair of racks 26 within each housing 16 are substantially evenly vertically spaced and are staggered vertically to lie in different horizontal planes relative to the respective teeth of the other pair of racks 26. The purpose of the staggered teeth 28 as well as the function of the tracks 22 and guideways 24 will be more fully explained.

As shown particularly in Figures 2 and 5, I have provided a pair of crossheads designated generally by reference numeral 30, one of which is adapted to slide within each of the opposite guideways 24 formed between the tracks 22. The specific structure of these crossheads is illustrated in greater detail in Fig. 5. Each crosshead comprises a pair of generally rectangular plates 32 at opposite sides of a similar pair of spacer plates 34 and held together in any convenient manner as by means of a through bolt 36 and associated nut 38. It will be noted that the spacer elements 34 are of slightly greater width than that of the tracks 22 so as to form channel-shaped runners between the plates 32 adapted to slidably receive the respective tracks 22.

Each of the inner plates 32 is provided with a notch 40 in its top edge adapted to receive one end 42 of a beam 44, preferably formed as an inverted T-shaped rail. The lower edges of the ends 42 of the rail 44 are provided with enlarged notches 46 so that when the ends 42 are inserted within the notches 40 (Figure 4) the beam 44 will be loosely engaged with the crossheads 30.

The outer plate 32 of each of the crossheads 30 has edge portions turned outwardly to form lugs 48. A pivot pin 50 is connected between the lugs 48 of each pair and a lever 52 is pivotally supported thereby. Each lever carries a transverse latch bar 54 attached thereto in any convenient manner and extending laterally from the opposite sides thereof. Each lever 52 is bent inwardly at its bottom end to form an actuating arm 56 adapted to extend through one of the guideways 24 and having an inclined abutment 58 at its inner end adapted to actuate the latch bar 54 in a manner to be described. A counter-weight 57 is carried by the lower end of each latch bar to tend to swing it inwardly.

At the top of the supports 12 I have provided pulleys 60 rotatably mounted upon brackets 62 secured in any convenient manner to the top ends of the members 20 as particularly shown in Figs. 1 and 3. Flexible cables or lines 64 extend over the pulleys 60 and are attached at one end to weights 66 freely vertically movable within the housings 16. The lines 64 are secured at their opposite ends to the crossheads 30 by looped members 68 secured to the bolts 36. As indicated above, a crosshead 30 is provided in each of the guideways 24, the transverse beam 44 being loosely engaged therewith. It will be apparent that the weights 66 are considerably heavier than the combined weights of the crossheads 30, the beam 44, and the carriage to be described below, and thus serve to continually urge the ends of the beam 44 upwardly.

Referring to Figs. 1 and 6, the carriage referred to above comprises a grooved wheel 70 in rolling contact with the upper edge of the rail 44 and freely movable therealong. A hanger 72 is rotatably mounted upon and depends from the axle 71 of the wheel 70 and carries a counterbalance 74 at the end of a rod 76 attached to the hanger 72 in any suitable manner as by means of a rivet or screw 78. The hanger 72 extends downwardly at opposite sides of the rail 44 in such manner as to prevent the carriage from dropping in the event the wheel 70 should become disengaged from the rail 44. It should also be particularly noted that the counterbalance 74 as illustrated in Fig. 1 is positioned beneath the carriage in such manner as to engage the abutments 58 of the actuating arms 56 at the opposite limits of its travel along the rail 44 for a reason which will be explained.

A simulated animal figure 80 is supported by a pin 81, offset from the axle 71. The pin 81 passes through a pair of offset arms 82, held in spaced relation by a collar 84, and extending to one side of and preferably integral with the hanger 72. In the present case the animal figure has been selected to represent a monkey which is retained in approximately upright position by connecting a depending tail portion 86 thereof with the rivet 78.

Another wheel 88 is rigidly secured to the axle 71 coaxial with the grooved wheel 70 for rotation with the latter. A pin 90 mounted eccentrically upon the outer face of the wheel 88 is pivotally

connected to one end of a link 92 articulated as by means of a pivot pin 93 to another link 94 and the latter in turn is pivotally mounted at its opposite end upon the pivot pin 81. It will thus be apparent that as the grooved wheel 70 rolls along the rail 44 the wheel 88 is also caused to rotate thus imparting an oscillatory motion to the articulated arms 92 and 94 to simulate a pedaling action by the animal figure 80.

The operation of the device is as follows:

With the various relatively fixed portions of the framework such as the base 10 and upright supports 12 in assembled condition, the carriage is placed upon the rail 44 with the grooved wheel 70 in contact with the latter, by inserting one end of the rail between the arms 72. The ends of the transverse rail 44 are then loosely engaged with the oppositely disposed crossheads 30 as shown in Figure 4. The toy is set in operation by manually grasping the rail 44 and moving it downwardly between the supports 12 and into the solid line position illustrated in Fig. 1. In this lowermost position the latch bars 54 are in engagement with the lowermost teeth 28 of the opposite racks 26 as shown, for example, in full lines in Fig. 4, thus retaining each of the crossheads as well as the rail 44 and its carriage in lowered position against the elevating tendency of the weights 66 which have been raised upwardly and which, due to their greater weight, tend to urge the movable crossheads and associated structure upwardly. By reason of the vertically staggered arrangement of the respective opposite teeth of the racks 26, the rail 44 will occupy an inclined position relative to the horizontal plane, being tilted downwardly and to the left in the solid line position in Figure 1.

With the parts in the set condition illustrated in Fig. 1, the carriage is now permitted to roll down the inclined rail 44 or from the right-hand side to the extreme left-hand position illustrated in dotted lines in Fig. 1. Upon reaching the left-hand end of the rail 44, the counterbalance 74 strikes the abutment 58 causing the actuating arm 56 to move its associated rack bar 54 out of engagement with the teeth 28. During this operation, which is of only momentary duration, the lever 52 pivots momentarily about the pivot pin 50 under the impact of the counterbalance 74 and almost immediately returns to a substantially vertical position.

This pivoting motion of the lever 52 as shown in dotted lines in Fig. 4 however, is sufficient to disengage the latch bar 54 from one pair of the teeth 28 so that the left-hand crosshead 30 is free to move upwardly under the urging of its associated weight 66 until the latch bar 54 engages that pair of teeth 28 next above. This upward movement of the crosshead 30 of course also carries the left-hand end of the rail 44 upwardly approximately the same distance so that the rail 44 is now inclined in an opposite direction or is tilted downwardly to the right. The carriage will then move to the right along the rail 44 until the counterbalance 74 engages the abutment 58 upon the actuating arm 56 depending from the right-hand crosshead 30 at which time a sequence of operations identical to that just described will take place causing the right-hand crosshead to move upwardly thus tilting the rail 44 into a reversely inclined position similar to but above its original position.

The successive positions assumed by the rail 44 are illustrated schematically in Fig. 1 by the

inclined dotted lines, the arrows showing the direction of movement of the carriage for each position. It will be obvious that as long as the weights 66 continue to urge the crossheads 38 and rail 44 upwardly, the latter will continue to move in step-by-step manner, the carriage rolling back and forth along the rail to release the ends of the latter one at a time until the rail 44 reaches the uppermost limit of its travel. As previously mentioned, the articulated members 92, 94 will oscillate continuously during movement of the carriage back and forth across the rail 44 to simulate a pedaling action.

It will be obvious from the foregoing that I have provided an improved kinematic toy which may be readily assembled from a relatively few simple parts and which derives its motive power entirely from the force of gravity. Although in the preferred embodiment which I have chosen for purposes of illustration I have disclosed a pair of toothed rack bars at opposite sides of each of the guideways 24, it will be apparent that numerous equivalent mechanisms may be substituted therefor and that the positive tooth and latch bar engagement may even be eliminated in favor of various known frictional contact or other equivalent devices. In like manner, although I prefer to have the movable portions of the toy ascend during operation, it will be apparent that by the provision of suitable reverse latch actuating mechanism the weights 66 could be eliminated and the movable elements permitted to descend under the action of gravity during operation of the toy.

I claim:

1. A toy comprising a base, a pair of spaced upright supports at opposite ends of said base each including a pair of spaced walls forming a vertical guideway, and a generally tubular housing, vertical racks within said housings having substantially evenly spaced teeth, the teeth of one rack being staggered vertically to lie in different horizontal planes than the teeth of the other rack, a pulley mounted adjacent the top of each housing and having a flexible line extending thereover, a weight attached to one end of each of said lines for vertical movement within the associated housing, a crosshead attached to the other end of each line and including a runner slidably engaged in the associated guideway, a depending lever pivotally attached to each crosshead and including a laterally extending latch bar at its lower end successively engageable with the associated teeth and an actuating arm extending through the associated guideway, an inverted T-shape rail loosely engaged with said crossheads and extending therebetween, a carriage including a grooved wheel in rolling contact with said rail, and a counterbalance depending from said carriage and alternately engageable with said actuating arms for disengaging said latch bars from said teeth whereby said weights alternately move the corresponding ends of said rail upwardly to successively reverse inclined positions to cause said carriage to travel back and forth along said rail between said supports.

2. A toy comprising a base, a pair of spaced upright supports at opposite ends of said base each including a pair of spaced walls forming a vertical guideway, and a generally tubular housing, vertical racks within said housings having

substantially evenly spaced teeth, the teeth of one rack being staggered vertically to lie in different horizontal planes than the teeth of the other rack, a pulley mounted adjacent the top of each housing and having a flexible line extending thereover, a weight attached to one end of each of said lines for vertical movement within the associated housing, a crosshead attached to the other end of each line and including a runner slidably engaged in the associated guideway, a depending lever pivotally attached to each crosshead and including a laterally extending latch bar at its lower end successively engageable with the associated teeth and an actuating arm extending through the associated guideway, an inverted T-shape rail loosely engaged with said crossheads and extending therebetween, a carriage including a grooved wheel in rolling contact with said rail, and a counterbalance depending from said carriage and alternately engageable with said actuating arms for disengaging said latch bars from said teeth whereby said weights alternately move the corresponding ends of said rail upwardly to successively reverse inclined positions to cause said carriage to travel back and forth along said rail between said supports.

3. A toy comprising a base, a pair of spaced upright supports at opposite ends of said base each including a pair of spaced walls forming a vertical guideway, vertical racks adjacent said guideways having substantially evenly spaced teeth, the teeth of one rack being staggered vertically to lie in different horizontal planes than the teeth of the other rack, a crosshead including a runner slidably engaged with each guideway for reciprocation therewithin, means urging said crossheads upwardly, a depending lever pivotally attached to each crosshead including laterally extending latch bars at its lower end successively engageable with the associated teeth and an actuating arm extending through the associated guideway, an inverted T-shape rail loosely engaged with said crossheads and extending therebetween, a carriage including a grooved wheel in rolling contact with said rail, and a counterbalance depending from said carriage and alternately engageable with said actuating arms for disengaging said latch bars from said teeth whereby said rail will move upwardly to successively reverse inclined positions to cause said carriage to travel back and forth along said rail between said supports.

4. A toy comprising a base, a pair of spaced upright supports at opposite ends of said base each including a vertical guideway, vertical racks adjacent said guideways having substantially evenly spaced teeth, the teeth of one rack being staggered vertically to lie in different horizontal planes than the teeth of the other rack, a crosshead mounted for reciprocation in each guideway, means urging said crossheads upwardly, a depending lever pivotally attached to each crosshead and including laterally extending latch bars at its lower end successively engageable with the teeth of the associated rack and an actuating arm extending through the associated guideway, an inverted T-shape rail loosely engaged with said crossheads and extending therebetween, a carriage including a grooved wheel in rolling contact with said rail, and a counterbalance depending from said carriage and alternately engageable with said actuating arms for disengaging said latch bars from said teeth whereby said rail will move upwardly to successively reverse inclined

positions to cause said carriage to travel back and forth along said rail between said supports.

5. A toy comprising a pair of spaced upright supports each including a substantially vertical guideway, a substantially vertical rack adjacent each of said guideways including uniformly spaced teeth thereon, the teeth of each rack being respectively vertically staggered relative to the teeth of the other rack to lie in different horizontal planes, a crosshead having reciprocating engagement with each guideway, means urging said crossheads upwardly, a depending lever pivotally attached to each crosshead and including a laterally extending latch bar at its lower end successively engageable with the teeth of the associated rack, and an actuating arm extending through the associated guideway, an inverted T-shape rail loosely engaged with said crossheads and extending therebetween, a carriage including a grooved wheel in rolling contact with said rail, and a counterbalance depending from said carriage and alternately engageable with said actuating arms for disengaging said latch bars from said teeth whereby said rail will move upwardly to successively reversely inclined positions to cause said carriage to travel back and forth therealong between said supports.

6. A toy comprising a pair of spaced upright supports each including a substantially vertical guideway, a substantially vertical rack adjacent each of said guideways including uniformly spaced teeth thereon, the teeth of each rack being respectively vertically staggered relative to the teeth of the other rack to lie in different horizontal planes, a crosshead having reciprocating engagement with each guideway, means urging said crossheads upwardly, latch means depending from each crosshead and successively engageable with the adjacent teeth, a rail loosely engaged with said crossheads and extending therebetween, a carriage including a grooved wheel in rolling contact with said rail, and a counterbalance depending from said carriage and alternately engageable with said latch means for disengaging the latter from said teeth whereby said rail will move upwardly to successively reversely inclined positions to cause said carriage to travel back and forth along said rail between said supports.

7. A toy comprising a pair of spaced upright supports each having a guideway, a rack adjacent each of said guideways including a plurality of teeth thereon, the teeth of each rack being respectively vertically staggered relative to the teeth of the other rack to lie in different horizontal planes, a crosshead mounted for reciprocation within each guideway, means urging said crossheads upwardly, latch means carried by each crosshead and successively engageable with the adjacent teeth, a rail loosely engaged with said crossheads and extending therebetween, and a carriage movable along said rail, said carriage having a tripping portion alternately engageable with said latch means for disengaging the latter from said teeth to release alternate ends of said rail for movement upwardly to successively reversely inclined positions to cause said carriage to travel back and forth along said rail between said supports.

8. A toy comprising a pair of spaced upright supports each having a guideway, a rack adjacent each of said guideways including a plurality of teeth thereon, the teeth of each rack being respectively vertically staggered relative to the teeth of the other rack to lie in different hori-

zontal planes, a crosshead mounted for reciprocation in each guideway, latch means depending from each crosshead and successively engageable with the adjacent teeth, a rail loosely engaged with said crossheads and extending therebetween, and a carriage movable along said rail, said carriage having a tripping portion alternately engageable with said latch means for disengaging the latter from said teeth whereby said

5 rail may move relative to said supports to successively reversely inclined positions to cause said carriage to travel back and forth therealong between said supports.

9. A toy comprising a pair of spaced upright supports, a plurality of teeth on each of said supports, the teeth on each support being respectively vertically staggered relative to the respective teeth on the other support, a crosshead movably mounted on each support, latch means on each crosshead successively engageable with the associated teeth, a transverse beam loosely engaged with said crossheads, and a carriage movable along said beam, said carriage having a tripping portion alternately engageable with said latch means for disengaging the latter from said teeth to result in movement of said beam relative to said supports to successively reversely inclined positions to cause said carriage to travel back and forth along said beam between said supports.

10. A toy comprising a pair of spaced upright supports, a plurality of teeth on each of said supports, the teeth on each support being respectively vertically staggered relative to the respective teeth on the other support, a structure 35 including a transverse beam mounted for vertical movement between said supports, latch means adjacent each end of said beam successively engageable with the adjacent teeth, and a carriage movable along said beam, said carriage having a tripping portion alternately engageable with each latch means for disengaging the latter from the adjacent teeth whereby said beam may move relative to said supports to successively reversely inclined positions to cause said carriage to travel 40 back and forth therealong between said supports.

11. A toy comprising a pair of spaced upright supports, a structure including a transverse beam mounted for vertical movement between said supports, latch means connected to said structure 50 adjacent opposite ends of said beam and releasably engaged with said supports, and a carriage movable along said beam and including a tripping portion alternately engageable with said latch means for disengaging the latter from said supports whereby said beam may move relative to said supports to successively reversely inclined positions to cause said carriage to travel by gravity back and forth therealong between said supports.

12. A toy comprising a beam, a pair of spaced upright supports each having a plurality of vertically spaced stop elements, the stop elements of each upright support being staggered relative to the respective stop elements of the other upright support whereby, when its ends are engaged with stop elements of the upright supports, said beam is inclined from the horizontal, and a wheeled figure mounted on said beam to travel therealong by gravity toward the lower end 60 thereof and operative adjacent such end of the beam for disengaging one end thereof from the stop element with which it is engaged to release said one end of said beam for movement to a next adjacent stop element of the same upright support to reverse the inclination of said beam.

13. A toy comprising a beam, a pair of spaced upright supports each having a plurality of vertically spaced stop elements, the stop elements of each upright support being staggered relative to the respective stop elements of the other upright support whereby, when its ends are engaged with stop elements of the upright supports, said beam is inclined from the horizontal, and means for disengaging one end of said beam from the stop element with which it is engaged whereby such end of said beam is released for movement to a next adjacent stop element of the same upright support, said releasing means comprising a wheeled figure mounted on said beam for movement by gravity toward the lower end thereof and operative when it reaches a point adjacent such end of the beam for releasing said one end of the beam from the stop element with which it is engaged.

14. A toy comprising a beam, a pair of spaced upright supports each having a plurality of vertically spaced stop elements, the stop elements of each upright support being staggered relative to the respective stop elements of the other upright support whereby, when its ends are engaged with stop elements of the upright supports, said beam is inclined from the horizontal, and means, comprising a wheeled figure mounted for movement along said beam by gravity toward the lower end

thereof, operative when said figure reaches approximately the lower end of said beam, for disengaging one end of said beam from the stop element with which it is engaged to release said one end of said beam for movement into engagement with a next adjacent stop element to reverse the inclination of said beam.

15. A toy comprising a beam, a pair of spaced upright supports each having a plurality of vertically spaced stop elements, the stop elements of each upright support being staggered relative to the respective stop elements of the other upright support whereby, when its ends are engaged with stop elements of the upright supports, said beam is inclined from the horizontal, each end of said beam being biased for vertical movement in one direction toward the next adjacent stop element, and means, comprising a wheeled figure mounted to roll on said beam toward the lower end thereof, for disengaging one end of said beam from the stop element with which it is engaged when said figure reaches the lower end of said beam, whereby said one end of said beam moves into engagement with the next adjacent stop element.
